UNITED STATES PATENT OFFICE

136,248

DESIGN FOR A DRESS

Samuel Zahn, New York, N. Y.

Application July 31, 1943, Serial No. 110,818

Term of patent 3½ years

To all whom it may concern:

Be it known that I, Samuel Zahn, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof.

I claim:

The ornamental design for a dress, substantially as shown.

SAMUEL ZAHN.
